UNITED STATES PATENT OFFICE.

JOHN PRUE KARNS, OF BOULDER, COLORADO, ASSIGNOR TO THE J. P. KARNS TUNNELING MACHINE CO., OF BOULDER, COLORADO.

DRILLING-MACHINE.

No. 892,849.

Specification of Letters Patent.

Patented July 7, 1908.

Application filed February 23, 1907. Serial No. 358,867.

To all whom it may concern:

Be it known that I, JOHN PRUE KARNS, a citizen of the United States, residing at Boulder, in the county of Boulder and State of Colorado, have invented a new and useful 5 Drilling-Machine, of which the following is a specification.

This invention has reference to improvements in drilling machines particularly 10 adapted for use in drilling tunnels, drifts, air-shafts, and the like.

One of the objects of the present invention is to provide a means for supporting the 15 drill-head, shaft and other parts upon adjustable supports on a truck or carrier in such manner that the drill-head shaft may be maintained at all times in the plane of the desired line of travel even when the truck or carrier may deviate therefrom due to 20 various causes that may arise during the progress of driving a tunnel.

It is also an object of the invention to provide means whereby a lateral movement of the drill-head relative to the truck or carriage 25 may be effected, so that the device may be arranged for driving a tunnel through an arc of any desired radius instead of in a straight line.

It is a further object of the invention to 30 balance the machine by placing upon the shaft carrying the drill-head a number of counterweights that may be added to or taken from, and these counterweights are placed upon the drill-head shaft beyond the 35 bearings for the same on the supporting truck at the end removed from the said drill-head, whereby the drill-head may be accurately counterbalanced under the varying conditions to which the machine may be 40 subjected when in use.

The several objects of my invention are realized in the machine which I will now proceed to describe and which is illustrated in the accompanying drawings, in which,—

45 Figure 1 is a longitudinal section, partly in elevation, of a drilling machine constructed in accordance with my invention; Fig. 2 is a face or front view of the drill head; Fig. 3 is a rear elevation of the machine with 50 the counterweights omitted; Fig. 4 is a cross-section through one of the journal boxes and some of the adjacent parts; Fig. 5 is a plan view, looking from below, of the two journal boxes and connecting parts; Fig. 6 is a top 55 plan view of the truck or carriage upon

which the drill-head bearings are mounted with the skeleton frame entering the same shown in transverse section; Fig. 7 is a detail section through a portion of the drill-head showing a portion of one of the cutter 60 blades and means for removably securing the same to the drill-head; this figure being drawn on a larger scale than the preceding figures; Figs. 8 and 9 are detailed views of different forms of reamer blades to illustrate 65 the provision for the coarse and fine adjustment thereof; Fig. 10 is a section, partly in elevation, of one of the anti-friction ball-carriers; Fig. 11 is an end view of the front 70 end of the main shaft where it carries the drill-head; Fig. 12 is a cross section, partly in elevation, of the mechanism for imparting a rotary motion to the drill-head shaft; Fig. 13 is a longitudinal section, partly in elevation, of the same structure; and Fig. 14 is 75 a detail of one of the supporting jackscrews and its removable seat.

Referring first to the drill-head, this structure, as shown in Figs. 1, 2 and 3, consists of a spider 1 of a diameter a little 80 less than the bore of the tunnel to be cut. This drill-head spider consists of a hub 2 from which project a number of radial arms 3 integral with a number of concentric rings 4, the outer one of which constitutes the periphery of the drill-head. Each arm 3 has formed on its rear face as an integral part thereof a web 5, and each ring 4 has formed on it a rearwardly-projecting web 6, the hub, arms, rings and webs 85 being all formed as one integral whole. Each web 5 extends from its corresponding arm to the rear end of the hub 2 at the point of juncture of these two parts, and this web is of gradually decreasing 90 width toward the periphery of the drill-head to a point near the web 6 on the outer ring 4. At this point the web gradually widens until it merges into the web 6 of the outer ring 4, which last-named web extends to the rear as far as the rear edge of the hub 2. About midway of the outer web 6 and formed on its inner face so as to project radially inward toward the center 100 of the drill-head is a short strengthening 105 web 7. The structure just described is such that the drill-head spider is braced in all directions and against strains that may come against its front face and no strain that may be brought to bear upon 110

any portion of said front face will be sufficient to deflect said front face from a substantially true plane. The hub 2 is formed with a boss 8 projecting beyond the front 5 face of the drill-head and on the front of this boss are mounted cutter-blades 9 at right angles to each other and extending diametrically across the face of said boss. The structure of these and the other cutter-blades 10 will be hereinafter described with reference to other figures of the drawings. Secured to the arms 3 tangential to the boss 8 are a number of cutter-blades 10 of a length sufficient to span two arms, as shown, 15 and beyond these tangential blades each arm carries a series of blades 11 parallel to the blades 10, and still further toward the periphery of the drill-head each arm has another set of parallel cutter-blades 12 20 shorter than the blades 11 and set at a slightly flatter angle to the arc described by all the blades as the drill-head rotates. Now, for structural reasons, the drill-head is made of two halves, as indicated in 25 the drawings, after the manner of an ordinary split pulley, and the meeting edges of these two halves are formed with arms 3 of less width than the other arms 3 but the combined width of two contiguous arms is 30 greater than that of any single arm 3 elsewhere located. For this reason the cutter-blades 10—11—12 secured to these arms are somewhat longer than those secured to the other arms, so as to straddle 35 the intervening space between the arms. The rings 4 of the drill-head are extended slightly beyond the adjacent arms 3, and the webs 5 are correspondingly thickened at these points to provide for the passage 40 of the securing bolts 13 by which the two halves of the drill-head are secured together. Between the arms, the drill-head is provided with a number of radial cutter-blades 14 extending from the innermost ring 4 to 45 the next adjacent outer ring 4, and from the latter ring to the peripheral ring 4 are a number of other cutter-blades 15 all of which latter are adjustable radially outward and constitute reamer blades as will 50 hereinafter appear. The several blades of the drill-head are secured to the spider by means best shown in Fig. 7.

In Fig. 7 only one of the arms 3 is shown and this will illustrate the manner of fastening the cutter-blades to the drill-head; however, these blades are carried both by the arms 3 and the rings 4. Formed in the outer face of the arm 3 is a groove 16 arranged at a suitable angle to receive the inner edge of one 60 of the cutter-blades, say, a cutter-blade 11. At one side of the groove 16 the arm 3 is formed with a rib 17, not shown in Fig. 7 but clearly shown in Fig. 2, and this rib terminates in an enlargement 18 through which extends 65 a perforation to the rear face of the arm 3,

which perforation receives the shank of an L-shaped bolt 19, that is, it has one end 20 bent at right angles and seated in a perforation 21 in the cutter-blade 11. The other end of the bolt 19 is threaded to receive a nut 22 by means of which the bolt 19 is secured to the arm 3 in a manner to hold the cutter-blades 11 firmly seated in the groove 16. By reference to Fig. 2 it will be seen that each blade is held to the drill-head by two or more 70 of the bolts 19. It will also be seen that the cutter-blades are thus securely held in their seats but at the same time, by removing the nuts 22, these cutter-blades may readily be removed. As shown in Fig. 7 and also in 80 Figs. 1 and 2, the cutting edge of each of these blades is formed into teeth 23, each generally frusto-pyramidal in shape with an elongated rectangular base and an elongated cutting face.

Those radial cutter blades 15 which I have termed reamer blades extend beyond the outer ring 4 of the drill-head and are there supported by brackets 24 integral with the ring 4 and projecting outward therefrom in a 90 radial direction. These brackets have grooves like the groove 16 in Fig. 7 and ribs 17 for receiving and supporting the cutter blades. The brackets serve as supports for those portions of the reamer blades which project beyond the periphery of the outer ring 4 and at the same time provide ample clearance space for the drill-head outside of said outer ring 4. These reamer blades project radially outward a short distance beyond the outer ends of the 100 brackets 24 and are there formed with radially projecting reamer teeth 25 in addition to the teeth 23, which latter are like those of the other blades. The reamer blades are cut away back of the teeth 25 so as to provide 105 clearance space and to provide for the wear of these teeth. The extent of radial projection of the teeth 25 of the reamer blades beyond the brackets 24 will determine the diameter of the bore of the tunnel as cut by the 110 drill-head.

In the operation of the machine the teeth 25 will be gradually worn off on their radially outward edges and provision is therefore made for adjusting these blades 15 radially 115 outward. In order to facilitate the adjustment of these blades there is provided a fine adjustment for some of them and a coarse adjustment for others. For instance, a certain few, say, four, of the reamer blades, equidistantly arranged around the periphery of the drill-head, are provided with smooth slots 120 26, as shown in Fig. 9, for the reception of the ends 20 of the bolts 19; and the rear faces of these particular blades are provided with one or more lugs 27 against which abuts an 125 adjusting set-screw 28 suitably threaded through a fixed stud on an appropriate portion of the drill-head. By simply loosening the nuts 22 of the bolts 19 a very delicate 130

balls jamming under the action of the large ball. The ball cups 44 are each provided with a central perforation 51 leading from the bottom of the receptacle 46, so that any particles of matter which may find their way into the receptacle 46 will ultimately escape through this passageway 51. When seated in the pockets 43 each cup 44 is adjustable in a radial direction to or from the shaft by means 10 of a set-screw 52. Within the lower half of the journal casing are placed as many of these ball-bearing units as space will permit for the weight of the part supported by these ball-bearing units is great and it is desirable 15 to reduce the friction to a minimum. The upper section of the journal casing is not provided with as many ball-bearing units, since this section of the casing is subjected to very little lateral thrust from the shaft, it 20 only being necessary to provide that the shaft be kept in strict alinement in its bearings so far as the upper ball-bearing units are concerned.

In order to provide for wear, the shaft 32 is 25 surrounded where it passes through each journal bearing, with a hardened steel sleeve 32' against which the ball-bearings engage and which, when worn, may be readily replaced with a new one without damage or 30 wear to the shaft itself.

It will be observed that in Figs. 1 and 4 the ball-bearing cups are shown as rectangular in cross section, while in Fig. 10 the edges are 35 chamfered. The purpose of this latter construction will be shown further on since the cups as illustrated in Fig. 10 are designed to be used in another part of the structure.

Before referring to the other parts connected with the bed-plate 37, I will first describe 40 the truck on which the weight of the structure is supported and by which the whole structure is permitted to be moved forward. This truck consists of two skeleton end-frames 53 joined at the sides by trusses 54, 45 the parts being firmly bolted together. At the lower corners of each skeleton frame 53 are formed journal bearings 55 for rollers 56. These rollers 56 are so supported by the journal bearings 55 that the plane of rotation of 50 the rollers on one side of the truck will intersect the plane of rotation of the rollers on the other side of the truck at the axis of the shaft 32; in other words, the rollers are arranged to rotate in planes radial to the axis of the journal. The bed-plate 37 between the two 55 lower sections of the journal casing is formed with a rectangular, downwardly-projecting skeleton frame 57 which enters the space formed between the truck members 53 and 60 the trusses 54, and this frame 57 acts as a guide for the journal bearing supports in the truck, so that the journal bearing supports may be moved vertically for a limited distance with relation to the truck and the fit of 65 the parts is sufficiently loose to permit a cer-

tain limited lateral swing of the journal bearings with relation to the truck. Adjacent to the four corners of the truck, which is substantially rectangular in general shape, are adjusting jackscrews 58 engaging in suitable nuts formed in the truck frame and having capstan heads 59 below the point of engagement with the bed-plate 37, at which latter point the bed-plate 37 is provided with elliptical seats 60 to receive the thrust of the jackscrews, and each of these seats is surrounded by an elliptical flange 61 to prevent possible disengagement of the jackscrew with the seat 60. By adjusting the four jackscrews, the journal bearings together with the shaft 32 and the drill-head may be lifted as desired to bring the shaft into alinement with the axis of the tunnel and to accommodate the truck to the various conditions that may arise. Other jackscrews 62 are provided adjacent to the jackscrews 58 and arranged at an angle both vertically and horizontally to the axis of the machine, one end 63 of the jackscrews being threaded and seated in a nut formed in the lower face of the bed-plate 37 and the other end in abutment with a lug 64 on the top of the adjacent portion of the truck frame near one of the jackscrews 58. The angle of the jackscrews 62 is such that they will tend to move the shaft and its bearings together with the drill-head horizontally upon a vertical axis substantially central to the bed-plate 37. The elliptical seats 60 and flanges 61 are curved on a radius struck from the center of the bed-plate 37 and thus constrain this bed-plate to move around a vertical axis when the jackscrews 62 are properly manipulated. The approximate extent of angular movement of the bed-plate 37 is indicated in Fig. 5 by the displacement of the dotted outlines with relation to the solid outlines. Primarily, the jackscrews 62 are intended to effect the slight angular movement of the drill-head in relation to the truck, so that where it is desired to drill a tunnel on a curve 110 this may be done when the plane of travel of the truck is out of alinement horizontally with the plane of travel of the shaft. In addition to this function, the jackscrews 62 also serve, when properly manipulated, to lock 115 the shaft and journal bearings together with the drill-head in the position to which they have been adjusted with relation to the truck. The frame 57 of the bed-plate 37 is, on being moved up and down in the pocket 120 therefor formed in the truck, subjected to more or less wear. For this purpose hardened steel wearing plates 65 are secured thereto at appropriate places and these plates may be readily replaced when worn.

In order that the drill-head and its supports may be prevented from lifting away from the truck, each upper half of the journal casing is provided with two radial thrust arms, best shown in Fig. 4 but also shown in 125 130

adjustment of the reamer blades 15 in a radially outward direction may be made, when the nuts 22 may be again tightened. This adjustment may be made again and again as occasion may require and in practice it will be made at comparatively frequent intervals. The rest of the reamer blades 15 are provided with similar slots 29, as best shown in Fig. 8, but instead of these 5 slots being smooth, as shown in Fig. 9, the bottom walls of the slots are formed into a series of curved seats 30 all of such size as to receive and seat the heads 20 of the bolts 19. These last-named reamer blades can therefore be adjusted only step-by-step, each step 10 representing a movement equal to the diametrical thickness of the head 20 of a bolt 19. Now, by adjusting the reamer blades 15 having the smooth slots 26, the diameter of the 15 bore of the tunnel has been kept true, but the reamer blades 15 having the coarse adjustment have been wearing away and becoming shorter and shorter. Ultimately this wearing away is equivalent to the width of one of 20 the seats 30, or, in other words, to the width of the head 20 of a bolt 19. When this occurs all of these coarsely-adjustable reamer blades may be moved radially outward a distance equal to the thickness of the head 20 25 of a bolt 19 and then locked in the adjusted 30 position.

The brackets 24 are provided at the rear with webs 31 for imparting strength thereto, and these webs are so spaced as to leave 35 room for the nuts of the bolts 19 which are provided for fastening the outer ends of the reamer blades to the drill-head.

In order that the teeth of the cutter-blades may reach every portion of the surface to be 40 cut, the teeth on adjacent cutter-blades are arranged to move, as the drill-head rotates, in arcs interposed between the arcs described by the teeth of adjacent cutter-blades.

It will be observed that the cutters on the 45 boss 8 project further forward than those on the rest of the drill-head, and this will cause the drill-head to cut a central or guiding passage into the end wall of the tunnel in advance of the main portion of the drill-head, 50 thus serving to lead the drill-head and maintain it in the plane of travel determined upon.

Coming, now, to the means of supporting the drill-head, there is shown a shaft 32, the front end of which is reduced in diameter and 55 formed into an approximately-rectangular portion 33 beyond which the shaft is again reduced into a substantially rectangular portion 34 and which terminates in a cylindrical portion 35. The hub 2 is similarly formed 60 with shouldered portions to receive the step portions 33-34 of the shaft and the cylindrical portion 35 thereof. The hub is secured to the portion 35 of the shaft by a key or pin 36 in the usual manner. Since, as will 65 hereinafter more fully appear, the shaft is

subjected to heavy end-thrust impacts, it will be seen that the step portions 33-34-35 form extended thrust bearings for the drill-head and the impact blows are therefore well distributed over this end of the shaft. Further than this it will be observed that the substantially rectangular portions 33-34 will cause the hub to rotate with the shaft without bringing undue strain upon the pin 36 and the reduced end 35 of the shaft. 70

In order to support the heavy weight of a structure of this character where the drill-head is many feet in diameter and heavy blows are delivered thereby, I have devised a special form of journal bearing and supporting truck therefor. The journal bearings, of which there are two suitably spaced apart are shown in Figs. 1, 3, 4 and 5. The two bearings and the spacing connection are in the form of a bed-plate 37 carrying at the 80 two ends semi-cylindrical lower portions 38-39 of the journal casing, all strengthened by a suitable web construction, as indicated in the drawings, but which need not be particularly described. The journal casings are 85 completed by the semi-cylindrical caps 40, also provided with strengthening webs, and these two parts, namely, the bottom half of each journal and the top half or cap thereof, are joined at their meeting faces by bolts 41 90 passing through flanges 42 provided for the purpose and in the manner common to structures of this character. Formed on the inner face of each lower half of the journal casing is a series of pockets 43 for ball-bearing cups 44, best shown in Fig. 10 though shown quite clearly but on a much smaller scale in Figs. 1 and 4. These ball-bearing 95 cups 44 are each composed of a cylindrical casting having a peripheral flange 45 at the 100 upper edge and a semi-spherical cup-shaped receptacle 46 for the balls constituting the ball-bearing. This ball-bearing is composed of a large ball 47 seated on a number of 105 smaller balls 48 embracing practically half 110 the surface of the large ball and disposed between the latter and the walls of the semi-spherical receptacle 46. The balls are retained within the cup by a top plate 48' having an opening 49 of suitable shape to permit 115 the ball 47 to project a distance and at the same time prevent it from leaving the pocket in which it is seated. The upper edge of the receptacle 46 is enlarged by a peripheral 120 groove 50, of such size as to permit the upper row of balls to play around the same freely, so that when the large ball 47 is rotated the balls are slowly carried down one side and up the other side into the free runway 50, when they will readily be diverted laterally and 125 quickly find their way around this runway to follow the downward stream of balls passing under the large ball 47. This free runway is an important feature of these ball-bearings 130 since it prevents any danger of the smaller

130

Figs. 1 and 3. These arms each consist of a bar 66 having its upper end bifurcated, as shown at 67, and there receiving the journals of a roller 68 adapted to travel along in contact with the walls of the upper section of the tunnel. The inner end of the bar 66 is seated in a pocket formed of two parts, one part 69 being formed upon the upper portion of the journal casing and the other part being separately formed and provided with a flange 71 bolted to a similar flange 72 formed on the part 69. Outside this pocket the bar 66 is threaded, as shown at 73, and there receives a headed nut 74, between the head of which and the end of the pocket 70 is a spring 75. Each thrust-rod 66 of one journal casing is connected by a bar 76 to the corresponding thrust-rod of the other upper journal casing, so that the said bars 66 will operate in pairs. These thrust-rod serve to maintain the shaft 32 and the journal bearings and parts carried thereby firmly seated on the truck, while at the same time they yield to any adjustment of the truck by means of the jackscrews before-mentioned. When it is desired to remove the machine from a tunnel or to retract it for any distance, these thrust-bars are removed by disengaging them from the upper journal casing at the flanges 71-72. Now, in order to counterbalance the weight of the drill-head, which is considerable, and thereby prevent an unequal strain upon the thrust-bars 66 and possible misalignment of the shaft with relation to the truck carrying the same, because there is no positive connection between the shaft journal structure and the said truck, that end of the shaft which is remote from the drill-head has placed upon it at a short distance from the rear journal support of the shaft a number of counterweights 77, the said shaft at this point being reduced, as shown at 78, to receive these weights, and by making the weights in several pieces it is possible to nicely adjust them to the exigencies of practical service. The drill-head shaft is in practice connected to a suitable steam driving mechanism which will cause a reciprocation of the shaft through a limited distance, the said shaft being connected directly to the piston of the driving mechanism and the truck being connected through braces 79 to the cylinder of said engine. This driving mechanism is not shown, since in itself it forms no part of the present invention, and any well-known form of driving mechanism which will produce the reciprocating action desired may be used; such, for instance, as is used in connection with steam hammers. Now, it is desirable in connection with the reciprocatory motion of the drill-head that it be slowly turned so as to bring the cutter-blade teeth against successively fresh portions of the surface to be cut and so chip the same away, the action being similar

to the action of a stone mason's chisel. For this purpose I have devised a rotary feed mechanism which will cause the shaft by its reciprocation to be slowly rotated. This means for rotating the drill-head is illustrated in Fig. 1 and on a larger scale in Figs. 12 and 13. Upon the shaft, at a point midway between the two journal casings of the shaft, there is secured to the latter a sleeve 80 by keys 81. This sleeve has in its outer surface grooves 82 extending longitudinally thereof at a slight angle to the plane of reciprocation of the said shaft. Encircling this sleeve is a narrow collar 83 carrying on its inner face a number of anti-friction balls 84 engaging and arranged to travel in the grooves 82 and held to the collar 83 by an annular plate 85 and engaging said collar 83 in longitudinal grooves 86 formed on its inner face. The plate 85 is held to the collar 83 by end-plates 87 fast thereon at each end so that this plate is confined to said collar by said end-plates 87. The collar 83 is mounted in a bearing composed of a lower section 88 formed integral with the bed-plate 37 midway between the two journal bearings for the shaft. The bearing of the collar 83 is completed by a cap-plate 89 secured to the bottom portion of the bearing by bolts 90 passing through ears 91 formed upon both parts of the journal bearing at the meeting edges thereof. The collar 83 is confined in the bearing from moving laterally therein by an inwardly-projecting annular flange 92 formed on each side of both parts of the bearing, and in order to reduce the friction between this collar and its journal to a minimum, a series of anti-friction balls 93 are arranged in suitable raceways formed in both the collar and the journal box adjacent to the flanges 92.

It will now be seen that when the shaft is reciprocated the inclined grooves 82 will tend to cause a rocking of the collar 83 about its axis, which latter is coincident with the axis of the shaft 32.

To restrict the rotary motion of the collar 83 to one direction only, the said collar has upon its periphery midway between its ends a continuous series of ratchet teeth 94, and in the cap portion 89 of the journal bearing are formed a number (there being eight shown in the drawings) of radial slots 95 in which play gravity pawls 96, the inner ends of which are arranged to engage the teeth 94 on the collar 83 when the latter is turned in one direction but to permit the teeth to lift the pawls and ride under the same when the collar is moved in the other direction. A large number of teeth are disposed around the collar 83 and for this reason the pawls are necessarily quite thin. In order, therefore, to increase their weight so that they will act promptly and by gravity only, they are made quite wide, as indicated in Fig. 13. In order

that these pawls may be readily removed when desired, an eye 97 is formed in the upper end of each where it projects from the slot receiving it. Since the pawls act by gravity alone, it is advisable to reduce the frictional contact between them and the walls of the slots, and for this purpose the walls are cut away both at the sides and ends of the pawls, as shown at 98, so that the pawls engage the slots only near the outer and inner portions thereof.

It will now be seen that when the shaft 32 is moved in one direction the grooves 82, acting through the anti-friction balls 84, will tend to turn the collar 83 in a direction and to an extent depending upon the pitch of the said grooves 82 to the plane of reciprocation of the said shaft, and when the shaft is moved in the other direction it will tend to return the collar 83 to its original position. Now, if the first movement of reciprocation tends to turn the collar in a direction to cause the teeth 94 to ride under the pawls, this collar will move rotatively for a distance corresponding to the angle of the grooves 82 to the plane of reciprocation of the shaft and also the extent of reciprocation of the shaft. When, however, the shaft is reciprocated in the reverse direction, this collar is held against return movement by certain of the pawls and the shaft is itself rotated for a distance equal to the rotative movement of the collar 83 caused by the first movement of the shaft.

In the operation of drilling it is customary to reciprocate the drill-head through different distances from a maximum to a minimum to strike blows of various force, as desired. The grooves 82 acting upon the collar 83 will therefore move this collar about its axis distances commensurate with the degree of reciprocation of the shaft 32. It is desirable that the shaft be rotated at every reciprocation. If but one pawl 96 were used, the shaft would be rotated only when the reciprocation was sufficient to cause a movement of the collar 83 sufficient to carry a tooth under that pawl. But sometimes the reciprocation is less and in such case no rotative feeding of the shaft would occur. To provide for this a number of pawls are used and are grouped so that more than one pawl will engage a tooth at a time, this latter effect, however, only being for the purpose of relieving the structure of too much strain, since a single pawl engaging a single tooth might in large machines result in stripping the tooth from the collar. Now, by arranging the pawls in series so that a number of pawls will cover a larger number of teeth, which number of teeth, however, is less than the lowest multiple of the number of pawls, provision is made for having a pawl of each series engage a tooth even though the shaft

be reciprocated but a fraction of its maximum reciprocation. Suppose the maximum reciprocation of the shaft will turn the collar 83 a distance of one tooth. Under such conditions the first pawl to the right of each series, as shown in Fig. 12, will each time engage a tooth 94. Suppose, now, that the operator desires to strike a lighter blow. The shaft is reciprocated to a less extent than formerly and the tooth engaged by the first pawl will no longer be carried from under the same to an extent sufficient to enable this pawl to engage the next tooth. One of the succeeding pawls, however, which are so spaced as to engage teeth at various points upon their inclined surfaces, will by this time have dropped in front of a tooth and will prevent the return movement of the collar 83, and, consequently, the shaft 32 will be rotated to a corresponding extent, although not that of the full length of a tooth. In the structure shown the minimum feed of the collar 83 which will cause a rotation of the shaft 32 is one quarter of the length of a tooth, since there are seven teeth embraced by any four successive pawls. With this structure it will be seen that to all practical purposes, whatever the length of stroke of the reciprocating shaft, there will always be a rotation of the same to an extent proportional to the extent of reciprocation of the shaft.

In order to provide for the reciprocatory motion of the shaft 32, the journal boxes for said shaft are located far enough apart to take in the mechanism described with reference to Figs. 12 and 13 for causing the progressive rotary feeding of the shaft and to allow for the reciprocation of the sleeve 80 which, when the shaft is reciprocated, rides through the collar 83 and its supporting parts.

The ball-bearings which constitute the journal bearings for the shaft 32 permit both reciprocatory and rotary motion of said shaft, as will be readily understood. It will be understood, however, that other types of anti-friction bearings may be used for the shaft and other parts instead of the ball-bearings herein described.

To provide additional support for the drill-head there is placed in front of the truck and on each side of the vertical axis of the machine supporting means for the drill-head comprising a segmental casting in the form of a rectangular plate 99 bent on an arc of which the axis of the shaft 32 is the center and on a radius slightly longer than the radius of the flange 6 of the outer ring 4 of the drill-head. Each of these plates 99, which are shown in Figs. 1 and 3, are provided with a number of ball cups 44, such as shown in Fig. 10, and these ball cups project through the plate and the lower faces are chamfered as shown at 100 in Fig. 10. On the outer face of each plate 99 are journaled

a number of rollers 101 in ears 102 formed on the said face and designed to travel on the contiguous wall of the tunnel behind the drill-head, while the balls 47 projecting from the other face of the plate engage the outer periphery of the flange 6 of the outer ring 4 of the drill-head. These plates serve to support in part the weight of the drill-head and constitute a broad bearing which will prevent the structure from sinking into the walls of the tunnel should, for instance, the front wheels of the truck on either sides or both happen to pass over a soft portion of the wall of the tunnel. Each plate 99 is connected to the front of the truck by the stay-rods 103 and 104, while the lower ends of the said plates are connected together by other stay-rods 105, so that these plates are rigidly supported. They are so placed as to permit the reciprocation of the drill-head with the shaft 32 without interference.

Now, let it be assumed that the machine is about to operate to drill a tunnel. The structure is moved to the proper point by any suitable means and the thrust-bars 66 are adjusted to the walls of the tunnel; also, the drill-head has been properly aligned and leveled by means of the jackscrews 58 and 62 and the counterbalance weights 77 have been properly placed, and the reamer blades have all been adjusted to cut a tunnel of the desired bore, the engine is started and the drill-head begins to reciprocate. The cutter-blades are brought into contact with the end 35 of the tunnel, those on the boss 8 cutting a small central guide bore in front of the main bore of the tunnel cut by the remaining blades. The reciprocation of the drill-head is continued and the said drill-head is slowly rotated as the cutting proceeds. From time to time it becomes necessary to adjust those reamer blades provided with the fine adjustment, and, at less frequent intervals, those provided with the coarse adjustment. As the machine progresses and soft spots in the tunnel may be encountered, the plates 99 will maintain the drill-head in alignment with the axis of the bore of the tunnel, since they provide a broad bearing for the front of the truck. From time to time it may become necessary to cause the machine to bore on a curve, in which case the shaft is turned at a slight angle to the line of travel of the truck by means of the jackscrews 62 as before explained. In this latter case it will be necessary, of course, to correspondingly adjust the supplemental supporting plates 99 by loosening up the rods 103, 104 and 105, and again fastening them in place after the adjustments have been made.

The drill-head may be fed forward toward the breast of the tunnel as the cut progresses in any suitable manner and by any suitable means, but as such means in itself forms no

part of the present invention and may, if desired, be of any known type adapted to the purpose, it is not shown in the drawings and no description thereof is deemed necessary.

The jackscrews 58 work in nuts formed in blocks 106, preferably made square and extending through square openings in the truck members 53 over the truck wheels. These openings are indicated in dotted lines at 107 in Fig. 6. Around the upper face of the block 106 is formed a flange 108 which engages the portion of the truck frame 53 immediately surrounding the opening 107 and so supports the block 106. By making the block 106 separate from the truck frame this block may be made of specially tempered steel and the nut for the jackscrew 58 may easily be formed therein. Also, the threads being subject to wear, the block may be readily replaced at any time without interference with the truck or necessitating the replacing of large and expensive castings. Since the weight of the shaft and parts carried thereby and the journal bearings for the shaft are all supported upon the jackscrews 58, the blocks 106 will be held in their seats in the truck frames 53 without any special fastening means.

I claim:

1. In a drilling machine, a rotatable drill-head, a shaft carrying said drill-head, journal bearings for the shaft, a truck, and adjusting screws carried by the truck and forming the sole support for but not connected to the journal bearings.

2. In a drilling machine, a drill-head, a shaft, journal bearings for the shaft, a truck, a guide on the journal bearings coacting with but not connected to the truck, and adjustable supports between the truck and the journal bearings.

3. In a drilling machine, a drill-head, a shaft, journal bearings for the shaft, a truck, a guide between the truck and the journal bearings, permitting the latter to move vertically, said guide being located midway of the journal bearings and movable in the truck, and vertically adjustable supports for the journal bearings located to the front and rear of said guide.

4. In a drilling machine, a drill-head, a shaft for the drill-head, journal bearings for the shaft, a truck, a guide between the truck and journal bearings, located midway of the latter and movable vertically in the truck, and adjusting screws carried by the truck at the front and rear of said guiding connection and engaging but not connected to the journal bearings.

5. In a drilling machine, a drill-head, a shaft and connected spaced journal bearings for the same, a truck, a guide located between the journal bearings and entering and mov-

- able vertically in the truck frame, and adjustable supports for the front and rear of said guide mounted upon the truck frame and supporting the journal bearings and 5 parts carried thereby.
6. In a drilling machine, a drill-head, a shaft and spaced journal bearings therefor, a guide formed on said journal bearings and movable therewith, a truck receiving said 10 guide, and vertically adjustable supports on said truck for said journal bearings.
7. In a drilling machine, a drill-head, a shaft and journal supports therefor connected and spaced apart in alinement with 15 said shaft, a guiding member formed on the bottom of the connected journal supports, a truck having an extended wheel base with a receptacle therebetween for the guide on the journal supports, and adjusting screws located above the wheels of the truck and engaging the journal supports.
8. In a drilling machine, a drill-head, a shaft and connected and spaced journal supports therefor, a guide member formed on said 20 journal supports intermediate of the same, a truck having an extended wheel base and composed of two joined wheel-carrying members and receiving the guide on the journal supports in the space between the said wheel-carrying members, and a number of jackscrews, each located over the wheels of the truck and carrying the weight of the drill-head, shaft and journal supports.
9. In a drilling machine, a drill-head, a shaft and journal supports for the same, a truck, jackscrews between the truck and the journal supports, and elliptical seats formed 25 on the journal supports.
10. In a drilling machine, a drill-head, a shaft and journal supports for the same, a truck, jackscrews carried by the truck and carrying the journal supports, and flanged elliptical seats on the journal supports for the jackscrews.
11. In a drilling machine, a drill-head, a shaft and journal supports for the same, a truck, adjusting means between the truck and the journal supports for moving the latter vertically, and other adjusting means between the truck and journal supports at each 30 end of said truck and journal supports for moving the latter in a horizontal plane around a vertical axis.
12. In a drilling machine, a drill-head, a shaft and journal supports for the same, a truck, jackscrews between the latter and the journal supports, flanged seats on the journal supports for the heads of the jackscrews, and means for moving the journal supports together with the shaft and drill-head in a horizontal plane upon a vertical axis.
13. In a drilling machine, a drill-head, a shaft and spaced journal supports for the same, a truck carrying said journal supports,
- and means for moving the latter upon the truck in a horizontal plane upon a vertical axis.
14. In a drilling machine, a drill-head, a shaft and journal supports for the same, a truck for carrying the journal supports, and jackscrews arranged at an angle to both the vertical and horizontal and located between the truck and journal supports for moving the latter in a horizontal plane upon a vertical axis.
15. In a drilling machine, a drill-head, a shaft and journal supports for the same, a truck, jackscrews between the truck and journal supports for supporting the latter and moving them vertically, other jackscrews between the truck and journal supports and arranged at an angle to both for moving the journal supports in a horizontal plane about a vertical axis, and elongated seats for the vertically-operating jackscrews provided with means for confining the heads of the screws to the seats.
16. In a drilling machine, a drill-head, a shaft therefor and carrying the drill-head at one end, journal supports for the shaft, a truck supporting but unsecured to the journal supports, and a counterweight beyond the journal supports and on that end of the shaft remote from the drill-head.
17. In a drilling machine, a drill-head, a shaft carrying the same at one end, spaced journal supports for the shaft, a truck carrying the journal supports but unconnected therewith, and a sectional counterweight upon the shaft beyond the journal supports at the end remote from that carrying the drill-head.
18. In a drilling machine, a drill-head, a shaft and journal supports therefor, a guide formed on the journal supports, a truck receiving said guide, adjusting screws for moving the journal supports vertically and carried by the truck, elliptical circumscribed seats for the vertically-moving adjusting screws, and other adjusting screws interposed between the truck and the journal supports at an angle and operating to move the said journal supports in a horizontal plane about a vertical axis.
19. In a drilling machine, a drill-head, a shaft carrying the same at one end, journal supports for said shaft, a truck carrying said journal supports, and a counterweight upon said shaft beyond the journal supports at the end remote from the end carrying the drill-head.
20. In a drilling machine, a drill-head, a shaft carrying the same at one end, spaced journal supports for the shaft, counterweights upon the shaft beyond the journal supports at the end remote from the drill-head, a truck having an extended wheel base, and carriers upon the truck upon which the

journal supports rest upon which they are balanced by the counterweights.

21. In a drilling machine, a drill-head, a shaft carrying the same at one end, spaced 5 and connected journal supports for the shaft, counterweights upon the shaft beyond the journal supports at the end remote from the drill-head, a truck with an extended wheel base, and adjusting screws near the ends of 10 the truck engaging the journal supports and constituting the sole carrier for the journal supports and the parts mounted thereon.

22. In a drilling machine, a drill-head, a shaft carrying the same at one end, spaced 15 and connected journal supports for the shaft, a guide formed upon said journal supports, a truck having an extended wheel base and receiving the guide on the journal supports, a counterweight on the shaft beyond 20 the journal supports at the end remote from the drill-head, and jackscrews carried by said truck over the wheels thereof and constituting the sole support for the journal boxes and parts carried thereby.

23. In a drilling machine, a drill-head, a shaft carrying the same, journal supports for the shaft, a truck upon which the journal supports are mounted, and yielding thrust-bars projecting from said journal supports 30 for engaging the upper walls of the bore formed by the said drilling machine.

24. In a drilling machine, a drill-head, a shaft carrying the same, journal supports for the shaft, a truck upon which the journal supports 35 are mounted, and radially-disposed upwardly-extending yielding thrust-bars on said journal supports.

25. In a drilling machine, a drill-head, a shaft carrying the same, spaced journal supports for the shaft, a traveling carrier for the 40 journal supports, and spaced yielding thrust-bars coacting with each journal support to maintain the shaft in alignment with the axis of the bore formed by said drilling machine.

26. In a drilling machine, a drill-head, a shaft carrying the same, journal supports for the shaft, thrust-bars carried by said journal supports and pocketed therein, springs surrounding said thrust-bars, and adjustable 50 abutments on the bars confining said springs between the said abutments and the ends of the pockets.

27. In a drilling machine, a drill-head, a shaft carrying the same, journal supports for the shaft, thrust-bearings projecting in an upward direction from said journal supports, pockets formed on said journal supports for receiving said thrust-bars, nuts engaging 60 threaded portions of said bars, and springs surrounding said bars and confined between the nuts and the ends of the pockets.

28. In a drilling machine, a drill-head, a shaft carrying the same, spaced journal sup-

ports for the shaft, a truck having radially-disposed wheels located in diametric planes cutting the journal supports for the shaft, and thrust bars mounted on the journal supports in the diametric planes of the truck 65 wheels and substantially diametrically opposed thereto.

29. In a drilling machine, a drill-head, a shaft carrying the same, spaced journal supports for the shaft, a truck having its wheels radially-disposed in diametric planes cutting 70 the journal supports, and radially-disposed yielding thrust bars removably secured to the journal supports and extending in the diametric planes of the truck wheels and substantially diametrically opposed thereto. 80

30. In a drilling machine, a drill-head, a shaft carrying the same, journal supports for the shaft having radially-disposed two-part pockets formed thereon, thrust-bars seated in said pockets, adjustable nuts carried by said 85 thrust-bars, and springs interposed between the said adjustable nuts and the ends of the pockets.

31. In a drilling machine, a drill-head, a shaft carried thereby, spaced journal supports for the shaft, a truck with wheels under each journal support and having their planes of rotation radially-disposed with relation to the axis of the shaft, and connected yielding 90 thrust-bars projecting radially upward from 95 said journal supports.

32. In a drilling machine, a rotatable and reciprocatory drill-head having a hub provided with a stepped socket, and a shaft for the drill-head having one end formed into a 100 series of shoulders engaging the face of the hub and the stepped portions of the socket in the hub.

33. In a drilling machine, a rotatable and reciprocatory drill-head having a hub formed 105 with a stepped socket with one or more portions of non-circular contour, and a supporting shaft for said drill-head having one end reduced and shouldered to fit the socket formed in the hub of the drill-head and also 110 to bear against the end of the hub.

34. In a drilling machine, a drill-head, a shaft carrying the same, journal bearings for the shaft, a truck on which the journal bearings are mounted, and bearing plates carried 115 by the truck and interposed between the periphery of the drill-head and the wall of the bore formed thereby.

35. In a drilling machine, a drill-head, a shaft carrying the same, journal supports for 120 the shaft, a truck upon which the journal supports are mounted, and bearing plates carried by said truck and interposed between the drill-head and the walls of the bore formed thereby, said bearing plates being provided 125 with rollers to engage the walls of the bore and anti-friction bearings to engage the periphery of the drill-head.

36. In a drilling machine, a drill head, a shaft carrying the same, journal bearings for the shaft, a truck, and adjustable supports for the journal bearings carried by the truck 5 and comprising jackscrews carrying said journal bearings and having removable nuts seated in the truck.

In testimony that I claim the foregoing as my own, I have hereto affixed my signature in the presence of two witnesses.

JOHN PRUE KARNS.
